UNITED STATES PATENT OFFICE.

VICTOR GERO, OF PHILADELPHIA, PENNSYLVANIA, ASSIGNOR TO PENNSYLVANIA
AXMINSTER CARPET CORP., OF PHILADELPHIA, PENNSYLVANIA, A CORPORATION
OF NEW YORK.

AXMINSTER LOOM.

Application filed January 11, 1927. Serial No. 160,419.

The present invention relates to weaving, and more particularly to an improvement in Axminster looms operating in the manner of the Crompton and Knowles looms.

5 In the weaving of Axminster carpets and rugs, it has long been the goal of manufacturers of this class of fabrics to produce a weave having such close woven characteristics as to produce a substantially flat back 10 with the face pattern showing thereon. While this goal has not heretofore been attained, it has been approached by manufacturers working with Royal Axminster and nipper type looms, but never by any one 15 employing looms working upon the principle of a three shot loom such as the Crompton and Knowles looms. In so far as this last type of looms is concerned, the field has been barren of progress toward a flat-backed 20 Axminster weave, and it has been heretofore considered impossible of accomplishment upon such a loom.

Some of the objects of the present invention are to produce upon a loom, operating 25 as does a Crompton & Knowles loom with three shots, an Axminster fabric having a substantially flat back; to produce upon such a loom an Axminster fabric upon which the pattern appears upon the back; to provide 30 an improvement in looms constructed and operating as does a Crompton and Knowles loom with three shots; to provide an improved Axminster weave; and to provide other improvements as will hereinafter 35 appear.

In the accompanying drawings Fig. 1 represents a fragmentary side elevation of the shuttle end of a Crompton and Knowles loom equipped with one form of the present invention; Fig. 2 represents a fragmentary front elevation of the same; Fig. 3 represents the cam side of one of the binder warp cams and showing in dotted lines the relative position of the companion binder warp 45 cam; Fig. 4 represents the cam side of the filler warp cam; Fig. 5 represents diagrammatically the respective heddle frame cycles; Fig. 6 represents a side of the comb control cam; Fig. 7 represents a detail in side elevation of the needle end of the loom with parts broken away for clear illustration; Fig. 8 is a diagram illustrating the weaving of the binder and filler warp, the weft and the tufts as the fabric would appear without

the beating steps; and Fig. 9 represents a 55 perspective of the fabric as woven by the loom of the present invention.

Referring to the drawings, those parts only of a Crompton and Knowles or three shot type of Axminster loom are shown 60 which will make possible a clear understanding of the present invention, and generally considered consist of the loom frame 10, heddle frames 11, 11^a and 11^b, spools 12, tuft yarn frames 13, the comb 14, knife bar 15, reed 16, looper finger 17, and needle 19. The heddle frames 11, 11^a and 11^b are respectively suspended from rocker arms 18, 18^a and 18^b, which are pivoted to a bracket pin 20 fixed to the main frame 10. These rocker 70 arms are respectively actuated by rods 21 under the control of rollers 22 respectively actuated by cams 23, 24 and 25, which in accordance with the present invention are quite different from the cams heretofore employed in this type of Axminster loom for operating the heddle rocker arms and will hereinafter be described in detail. The spools 12 and tuft yarn frames 13 are operated and automatically handled in the manner usual in looms of this type. The comb 14 is carried by an angle piece 26 supported by arms 27 pivoted to crank arms 28 which are fixed to a rock shaft 30, the latter receiving 80 its rocking movement from an arm 31 joined by a connecting rod 32 to a cam roller supporting link 33. The action of the rock shaft 30 is to advance the comb 14 at the proper time in the cycle of operations, and as this particular movement is unchanged 85 from that of looms in present day use, it is believed unnecessary to specifically show and describe the cam by which the link 33 is controlled. This movement of the comb 14 referred to as old concerns only the advance 90 of the comb since its rise and fall movement has been materially changed in order to accomplish, with certain other new adjuncts of the mechanism, the new result in so far as this particular type of loom is concerned. Brackets 34 serve as guide supports for the 95 comb piece 26 during its movement toward and away from the yarn tufts. The knife bar 15 is carried by pivoted arms 35 and is operated in the usual way in timed relation 100 to the associated parts. The reed 16 is also arranged to be rocked to beat up the shots and is operated by the usual mechanism in

105

such looms. The finger 17 is carried by a rock arm 36 pivoted to the frame 10 or other fixed part and is arranged to be thrown up to engage the shots by a spring 37 which is stretched and maintained under tension from a fixed point 38. The arm 36 is released to the action of the spring 37 periodically through a connecting rod 40 which joins a pivoted arm 41 having a cam roller 42 riding upon a cam 43. This cam 43 has dwells 44 whereby the arm 36 and its connected parts are freed to the action of the spring 37.

Referring now to Fig. 9, a fabric woven by the present invention is shown having the desired flat back 45 with the face design 46 showing through upon such back. Axminster weaving in some degree approaching the product of the present invention has been carried out upon looms operating differently from looms of the Crompton and Knowles types, but the resulting product is not as truly flat-backed as that produced by the present loom invention, nor is it as closely woven and bound. The fabric formed by the present invention consists of two binder warps 50 and 51, a filling or "stuffer" warp 52, and three shots of weft 53, 54 and 55 to each row of tufts 56. A shot is considered as the full travel of the needle in and out of the warp harness, and in the weaving of this fabric the shot 53 is the one about which a tuft is combed and lies between the binders 50 and 51 but above the stuffer warp 52. The shot 54 lies below the tuft but between the binders 50 and 51 and below the stuffer warp 52. The shot 55 lies between two adjacent tufts between the binders 50 and 51 and above the stuffer warp 52. These shots are bound into the fabric by alternately raising and lowering the heddle frames 11^a and 11^b so that the binder warp 50 winds under the shot 54 and over the shots 53 and 55 of the next row of tufts, while the binder warp 51 winds over the shots 53 and 55 and under the shot 54 of the next row of tufts, and this alternate over and under weaving continues throughout the fabric and is diagrammatically shown in Fig. 8. It is to be understood, however, that this illustration is for the purposes of example, and that in the weaving the actual relative positions of the shots are as shown in Fig. 9.

For the rise and fall movement of the heddle frames 11^a and 11^b two side face cams 23 and 24 are provided, each having the same configuration of cam groove 60 and both mounted on the driven shaft 61 but angularly disposed with respect to each other so that the heddle frame 11^a is up when the heddle frame 11^b is down. The cam groove 60 is formed with a relatively long high point dwell "A" followed by a low point dwell "B," then a short intermediate dwell "C" substantially midway be-

tween the high and low points, which is followed by a second intermediate point dwell "D" of the same length as the dwell "A," and this in turn runs into a short high point dwell "E" followed by an intermediate dwell "F" which merges into the dwell "A" at the cycle end. The full line in the diagram Fig. 5 represents the movement of the heddle frame 11^a under the actuation of the cam 23, while the dotted line on the same figure represents the movement of the heddle frame 11^b under actuation by the cam 24, and thus graphically give the relation between the binder warps 50 and 51 for a complete operating cycle.

For controlling the rise and fall of the filling or stuffer warp 52, a cam 25 is provided, having a cam groove 63 forming two diametrically opposite high point dwells "G" and "I" and two low point dwells "H" and "J" diametrically opposite each other but at 90 degrees with respect to the dwells "G" and "I." These low point dwells "H" and "J" correspond radially with the intermediate point dwells "C" and "F" of the cams 57 and 58, and in assembled condition the cam 62 is fixed to the shaft 61 so that the two low point dwells "H" and "J" coincide with the angular position of the intermediate dwells "C" and "F" of the other two cams. The movement of the heddle frame for the stuffer warp 52 is graphically illustrated by the double line of Fig. 5.

For raising and lowering the comb 14 in proper timed relation, the angle piece 26 is fixed to rods 64 which are fast at their lower ends to a cross rod 65 which is raised by and operated by a bell crank 66 journaled upon a rod 67 and operated by a connecting rod 68 from a link 70. The cam roller 71 is carried by the link 70 and bears against the face of a cam 72 fixed to the shaft 61, and the bearing relation of the roller to the cam is maintained by a spring 73 which functions also to withdraw the cam in accordance with the changed relation between the cam 72 and its roller 71. In connection with this cam 72, it should be noted that its contour is such as to cause the comb 14 to be quickly withdrawn at the end of the second shot of the weft, so that it will be out of the way by the time the reed 16 beats this second shot into the fabric.

In order to produce a uniform, smooth selavage edge at the needle side of the fabric, provision is made for preventing the finger 17 coming into play upon its second shot by mounting a stop 74 upon the knife bar projecting beyond the edge of the knife 75 and of sufficient length to project into the path of the finger arm 36 when the knife is in cutting position. From this it will be seen that upon the second shot of the weft the stop 74 will prevent the rise of the finger 17 and its function for that particular

shot will be taken by the comb 14. This construction allows each shot of weft to be drawn evenly into the fabric during the operation of the reed, and eliminates the 5 irregular edge which would result were the finger 17 to perform its usual function of looping while the comb was still in position. This irregular edge is caused by the small extra length loops which are formed 10 when the shot is looped about both the comb and the finger 17.

In order to operate the heddle cams 23, 24 and 25 in proper timed relation with the other adjuncts of the weaving mechanism, 15 the aforesaid cams are fixed to a hub 76, which is loosely journalled on the shaft 61 but driven therefrom by reduction gearing 77, whereby the driven shaft 61 makes two revolutions while the hub and cams make 20 but one.

In the weaving of the fabric of the present invention the first shot of the weft takes place when the cam 23 is in the position with the dwell "A" holding the handle frame of binders 51 raised and the finger 17 automatically rises to allow the shot to loop. The tuft yarn frame 13 lowers to position the row of tufts and the comb 14 combs the tuft about the shot while acting as a holder to allow 30 the second shot to loop. This latter action is brought about by the advance of the knife 75 to which is attached the stop 74 and this latter is held in the path of the arm 36 to prevent the finger 17 from rising. This is 35 an important feature in the weaving because the absence of the finger 17 between the yarn and the comb prevents a small edge loop being formed which gives a rough and uneven selvage. Both the first and second 40 shots 53 and 55 pass between one set of binder warp and the filler warp 52 when the former is raised, while the third shot 54 passes between the filler warp 52 and the other set of binder warp when the latter is 45 down. It will be seen from Fig. 8 that the two sets of binder warp are alternately raised and lowered while the binder warp maintains its generally centrally disposed 50 position. In connection with the action of the comb, attention is directed to the cam 72, which is so shortened as to allow the comb to automatically drop quickly away from the harness immediately after the second shot is completed in order to be out of the 55 path of the reed 16 during its beating movement. The present construction operates to produce a relatively close weave and one in which the second and third shots are beaten to a position substantially one above the other and with the second shot flush with the tuft body. In this way the usual space between adjacent rows of tufts is eliminated and instead of well defined depressions 60 throughout the back of the fabric, there is a 65 substantially solid fabric, or solid to the ex-

tent that all of its parts lie in the same plane to give a uniform smooth surface upon which the design appears by reason of the exposed tufts.

In the formation of the flat back fabric 70 by the present invention, the decreased speed of the warp cams relative to the main shaft bears a precise relation to the operation of the reed, the looping finger, and the comb control. Thus, as a means for ensuring a 75 flat back while also maintaining a uniform edge appearance by the three shot operation, it is necessary to eliminate one operation of the looping finger while still allowing looping to take place. In other words, if the 80 looping finger were to function on each shot, as it normally does in two and three shot weaving, there would have to be an interval for the operation of the comb after one of the shots and this interruption of the cycle 85 causes the uneven back finish which the present invention avoids. In accordance with the invention, the looping finger is rendered inoperative on the second shot of the weft and the comb is brought up and 90 performs two functions, one its ordinary one of combing the tufts and the other of looping the weft.

While only a single form is shown in 95 which this invention may be embodied, it is to be understood that the invention is not limited to any specific construction, but might be applied to various forms without departing from the spirit of the invention or the scope of the appended claims.

Having thus described my invention, I claim:

1. In an Axminster loom of the three shot type, two sets of binder warp and one set of filler warp, means for successively throwing three successive shots of wefts across said warp sets for each row of tufts, means for raising and lowering said sets of warp in a predetermined manner, a finger automatically operable to loop said shots, a comb, means operable during one shot to hold said comb to loop such shot, and means automatically operable on said comb loop shot for rendering said looping finger ineffective, whereby a uniform-edge fabric is 110 woven.

2. In an Axminster loom of the three shot type, a main shaft, a plurality of heddle cams, means for rotating said cams at a speed different from the speed of rotation of said main shaft, a looping finger, means for moving said finger to looping position, a comb, means for causing said comb to act as a looping finger on one of the three shots of said loom while simultaneously carrying out a combing operation, and a device for holding said looping finger inoperative on said comb stroke.

3. In an Axminster loom of the three shot 130 type, a main shaft, a plurality of heddle

cams, means for rotating said cams at a speed different from the speed of rotation of said main shaft, a looping finger, means for moving said finger to looping position, a comb, means for causing said comb to act as a looping finger on one of the three shots of said loom while simultaneously carrying out a combing operation, a device for holding said looping finger inoperative on said comb stroke, and a reed arranged to beat each of said three shots.

4. In an Axminster loom of the three shot type, a main shaft, a plurality of heddle

cams, means for rotating said cams, a looping finger, means for moving said finger to looping position, a comb, means for causing said comb to act as a looping finger on one of the three shots of said loom while simultaneously carrying out a comb operation, and a device for holding said looping finger inoperative on said comb stroke.

Signed at Philadelphia, county of Philadelphia, State of Pennsylvania, this 3rd day of January, 1927.

VICTOR GERO.
